Attorney, Agent, or Firm—Merchant & Gould P.C.[57] **CLAIM**

The ornamental design for a storage holder, as shown and described.

DESCRIPTION

FIG. 1 is a side view of the storage holder according to the present invention, shown in the extended position and broken away for ease of illustration;

FIG. 2 is a front view of the storage holder shown in FIG. 1;

FIG. 3 is a rear view of the storage holder shown in FIG. 1;

FIG. 4 is a top end view of the storage holder shown in FIG. 1;

FIG. 5 is a bottom end view of the storage holder shown in FIG. 1; and,

FIG. 6 is a reduced perspective view of the storage holder of FIG. 1 shown assembled and holding an article, such article being provided in phantom and not forming a part of the present invention.

The pattern which is partially shown in FIGS. 2 and 3 is understood to repeat uniformly across the entire strap.
